UNITED STATES PATENT OFFICE.

WALTER S. LAKE, OF KANSAS CITY, MISSOURI.

BELT TIGHTENING AND CUTTING DEVICE.

Application filed November 27, 1922. Serial No. 603,620.

To all whom it may concern:

Be it known that I, WALTER S. LAKE, a citizen of the United States, and resident of Kansas City, Jackson County, State of Missouri, have invented a certain new and useful Improvement in Belt Tightening and Cutting Devices, of which the following is a complete specification.

This invention relates to belt tightening, cutting and fastening devices and has for its object to produce a device of the character mentioned which is so constructed and arranged that the belt may be properly tightened, cut with an absolutely square joint and then abutted against the other end of the belt and the two ends secured together by any suitable or preferred lacing, all of these operations being carried out without removing the belt from operative position.

20 A further object is to produce a device of this character of relatively small and light construction for convenience of portability, and which is also of simple and inexpensive construction.

25 With the objects named in view the invention consists in certain novel and useful features of construction and organization of parts as hereinafter described and claimed; and in order that it may be fully understood, reference is to be had to the accompanying drawings, in which:—

Figure 1 is a top plan view of the device; Figure 2 is a side view of the same; Figure 3 is a section on the line III—III of Figure 2;

35 Figure 4 is a section on the line IV—IV of Figure 3;

Figure 5 is a view similar to that of Figure 3, but illustrates the device as it will appear when a belt lacing of a preferred type has been placed in the device;

Figure 6 is an end view of a common and well known type of belt lacing; and

45 Figure 7 is a top plan view of a new type of belt lacing as it will appear when engaged with a belt.

In the said drawings, where like reference characters identify corresponding parts in all of the figures, 1 illustrates the base member of the device, said base member being formed with a longitudinal slot or opening 2 for the reception of a knife, hereinafter referred to.

55 Projecting at right angles to the base and at one end thereof, is a handle 3 for use in positioning the device, and at the other end,

the base member is formed with an upwardly projecting standard 4 terminating in a forwardly extending arm 5 parallel to and above the base and ending at a point about midway the length of the base.

The standard 4 is also formed with a pair of arms 6 and 7 projecting in opposite directions and curving around parallel to the base and at opposite sides and above the plane of the same.

The base 1 is formed at one side with an extension or abutment portion 8 underlying the end of the arm 7. At its opposite side, the base 1 is formed with a pair of outwardly projecting ears 9, between which is secured a roughened feed roller 10 keyed on an operating shaft 11, journaled in the ears 9 and equipped at its outer end in close proximity to the handle 3 with an operating knob 12, whereby said roller 10 may be rotated.

Secured in the slot 2 of the base is a belt-cutting knife 13 formed with an operating ear 14. The ear will at all times, project above the base through the slot 2, and the body of the knife is formed near its ends with a pair of semi-circular slots 15 for engagement with a pair of pins 16 spanning the slot 2. In this connection by reference to Figure 4, it will be noted that when the knife is in its elevated position, the pins 16 will be engaged in a part of the slots which is substantially at right angles to the vertical. It will therefore, be evident that direct downward pressure on the knife will be resisted by the pins and the knife will be maintained in position. When it is desired to lower the knife a downward and rearward movement is imparted to it by the operator through the ear 14, to cause it to slide downwardly and rearwardly being guided by the pins 16 in the slots 15.

In engagement with the end of the arm 7 is a clamping screw 17 equipped with an operating knob 18 at its upper end and provided with a swiveled clamping foot 19 formed with teeth, said clamping foot being adapted to clamp one end of a belt B down upon the extension 8 of the base 1. The other arm 6 is engaged by a clamping screw 20 provided with an operating knob 21 at its upper end. Swiveled on the lower end of the screw 20 is an inverted U-shaped bracket 22 between the arms of which is journaled a roller 23 in length substantially equal to the length of the corrugated roller 10 and adapted to clamp the belt B tightly.

down upon the feed roller 10, as will be described hereinbelow. In order to maintain the roller 10 in any predetermined position against the contracting tendency of the belt, 5 a ratchet pinion 10^a is keyed on the shaft 11 adjacent one of the ears 9, and pivoted on one of said ears 9 is a gravity pawl 10^b in engagement with the ratchet.

The extremity of the arm 5 is engaged by 10 a clamping screw 24 carrying at its lower end a swiveled bracket 25 to which is secured a pair of clamping bars 26 and 27 spaced slightly apart to provide a knife-receiving slot 28 and of substantially the 15 same length as the base 1, said bars 26 and 27 being secured together at their ends by a pair of cross straps 29. In order to hold the bars 26 and 27 against rotation, the rear strap 29 is notched to coincide with 20 the slot 28 and received within said notch and slot is a guide tongue 30 formed on the front face of the standard 4 (see Figure 4).

Keyed to the upper end of the screw 24 is an operating wheel 31 formed with a series 25 of ratchet teeth 32, and provided also with a plurality of straight sided teeth 33. The wheel 31 is received within the bifurcated end of an operating handle 34 loosely journaled on the screw 24, and mounted between 30 said bifurcated arms is a double acting dog 35 pivoted for operation on a pin 36 formed at its upper end with a projecting portion 37 for a purpose which will hereinafter appear. Secured in the handle and spaced 35 slightly from the pin 37 is a second pin 38 formed with a projecting head. The parts normally stand in the position shown in Figure 1, the dog being retained in the position shown by means of a spring 39 abutting 40 at its rear end against the pin 38, in which position the parts are ready to impart downward movement to the clamping bars 26 and 27. When it is desired to rotate the screw 24 in the opposite direction for the purpose 45 of elevating the bars 26 and 27, the free end of the spring 39 is disengaged from the pin 38 and is engaged with the pin 36. This action reverses the tendency of the 50 spring, and causes the other end of the dog to be depressed for engagement with any of the straight edged teeth 33, as will be readily understood.

For convenience in maintaining lacing devices of various kinds in position pending 55 their insertion into the extremities of a belt, the following devices are provided: Spanning the slot 28 and adapted for sliding longitudinally on bars 26-27 and resting thereon are a pair of plates 40, each formed with a tongue 41 depending through 60 the slot 28, said tongues being formed at their lower ends with flanges 42 respectively facing toward each other. It will be evident that the flanges 42 are adapted to 65 receive between themselves and the faces of

the bars 26 and 27, the end edges of any of the common and well-known type of belt lacing 42^a, for example, that illustrated in Figure 6. In order to secure the members 40 in position, they are pivoted near their rear 70 edges to a pair of securing clips 43 bent downwardly and engaged with the underface of the bars 26 and 27, as will be readily understood. The members 40 are ordinarily slid to the extreme limits of their 75 movement so as to be out of the way, as will be set forth in the description of the operation of the device, and when the knife is elevated and the bars 26 and 27 are lowered the plates 40 will be pivoted upwardly, the parts 41 and 42 being received within the slot 28, through contact with the edge of the knife.

In order to securely maintain in position a belt lacing 42^b formed of two members 85 pivoted centrally (see Figure 5), a thumb screw 44 is engaged through the bar 27 and its end is adapted to intersect the slot 28 between the pair of bars 26 and 27.

The hinge portion of the type of lacing 90 mentioned is inserted in the slot 28 (see Figure 5) and the lacing is securely retained in position under the pressure imposed on it by the thumb screw 44.

In the operation of the device one end of 95 the belt is inserted into position with its end flush with the slot 2 of the base and is clamped tightly in such position through the pressure imposed on it by the clamping foot 19 of the screw 17, against the extension 8 of the base.

The other end of the belt is inserted between the rollers 10 and 23, and clamped tightly between said rollers by operation of the clamp screw 20. The feed roller is now 105 rotated through its knob 12, thus stretching the belt and causing the adjusted end to overlap the other end, as shown in Figure 3, the pawl and ratchet mechanism 10^a and 10^b holding the adjusted end firmly in 110 the position above referred to.

The knife is now elevated through application of forward and upward pressure on its ear 14, and when in fully elevated position projects above the end of the belt which 115 overlies the extension 8 and underlies the overlapping end of the belt (see Figure 3). The clamping screw 24 is now rotated by means of its handle 34, the dog 35 engaging the teeth 32, and the clamping bars 26 and 120 27 exert clamping pressure on the belt at opposite sides of the knife, causing the knife to impinge on the belt with a shearing action and severing the extremity of said belt accurately and smoothly, the knife being received within the slot 28. Preliminary to the downward movement of the bars 26 and 27, the lacing supports 40 are moved to the opposite ends of the slot 28, and upon downward movement of said bars, the tongues 125 130

41 of said members 40 will be swung up into the slot as mentioned hereinabove. After the belt has been severed the clamping bars 26 and 27 are withdrawn from 5 clamping position through operation of the screw 24, the dog at this time engaging the teeth 33, and the severed end of the belt is removed and the knife is lowered. A lacing member of the common and well-known 10 type 42^a is now placed in the device, being supported by the flanges 42 of the adjustable plates 40 as pointed out hereinabove, or the preferred type of lacing 42^b may be employed and in this latter case, the 15 lacing will preferably be retained in position by means of the thumb screw 44.

Clamping pressure is again imparted to the bars 26 and 27, and the teeth of the lacing device will be forced through the ends 20 of the belt into engagement with the base 1 and thus clinched as common and well-known in the art. The pressure imposed by clamping screws 17, 20 and 24 is now relieved and the device removed from position, as will be readily understood.

In actual practice the engagement of the pins 16 with the slots 15 is depended upon to hold the knife rigid during the belt cutting operation, but it has been found 30 that accidental lowering movement is sometimes imparted to the knife. In order to guard against such movement a clamping screw 45 is in threaded engagement with the base 1 and intersects the slot 2 thereof

at any convenient point, so that the screw 35 may be operated to clamp the knife in its elevated or lowered position by abutment therewith as will be readily understood.

From the above description, it will be apparent that I have produced a device of 40 the character described which possesses all of the features of advantage pointed out as desirable; and while I have described and claimed the preferred embodiment of the same, I reserve the right to make all 45 changes properly falling within the spirit and scope of the appended claims.

What I claim is:

1. In a device of the character described, a base, a knife in said base, means to clamp 50 one end of a belt upon said base, means for stretching the belt and causing its other end to overlap the first-named end, and means to effect the severing of said overlapped end of the belt by said knife. 55

2. In a device of the character described, a base, means carried by said base for clamping one end of a belt thereto, means carried by said base for stretching the other end of said belt and causing such end to assume an overlapped relation with respect to the first-named end, a knife mounted in said base, and a clamping member for causing said overlapped end of the belt to be severed by said knife. 60 65

In witness whereof I hereunto affix my signature.

WALTER S. LAKE.
